SERVING TRAY FOR BEVERAGES OR THE LIKE

Catherine E. Thompson, 12205 Falkirk Lane,
West Los Angeles, Calif. 90049

Filed Jan. 15, 1968, Ser. No. 10,157

Term of patent 3½ years

Int. Cl. D7—01
U.S. Cl. D44—10

FIGURE 1 is a perspective view of a serving tray for beverages or the like showing my new design;

FIGURE 4 is a front elevation view thereof, with the shelf portion rotated 90° from its position as in FIGURES 1, 2 and 3.

I claim:

The ornamental design for a serving tray for beverages or the like, substantially as shown.
